CLAIM

The ornamental design for a hidden stackable folding glasses pendant, as shown and described.

DESCRIPTION

FIG. 1 is an isometric view of a hidden stackable folding glasses pendant, in a folded position, according to our new design;

FIG. 2 is a front view thereof;

FIG. 3 is a right-side view thereof;

FIG. 4 is a rear view thereof;

FIG. 5 is a left-side view thereof;

FIG. 6 is a top view thereof;

FIG. 7 is a bottom view thereof;

FIG. 8 is an isometric view of the hidden stackable folding glasses pendant of FIG. 1, in an unfolded position;

FIG. 9 is a front view thereof;

FIG. 10 is a right-side view thereof;

FIG. 11 is a rear view thereof;

FIG. 12 is a left-side view thereof;

FIG. 13 is a top view thereof; and,

FIG. 14 is a bottom view thereof.
